UNITED STATES PATENT OFFICE.

WILLIAM JOHNSTON, OF BOWESMONT, NORTH DAKOTA.

STOVE.

Application filed December 16, 1924. Serial No. 756,250.

To all whom it may concern:

Be it known that I, WILLIAM JOHNSTON, a citizen of the United States, residing at Bowesmont, in the county of Pembina and 5 State of North Dakota, have invented a new and useful Stove, of which the following is a specification.

This invention relates to stoves and has special reference to an improvement which 10 renders it practical to burn lignite or slack coal.

In places where lignite and similar soft coal is used in stoves and furnaces difficulty is experienced in obtaining proper combustion. 15 When the fuel has become slack, as lignite will after a considerable exposure to the air. When such coal is employed in stoves of ordinary construction gas explosions frequently occur and the fire is often smothered 20 by the application of new coal in considerable quantities. This is due to the fact that the fineness of the coal prevents the proper amount of air necessary for combustion from penetrating the coal with the result that explosive gases are generated and pass upwardly 25 into the combustion chamber where they are ignited from sparks or flames that escape from the bed of burning coal.

This coal when burning produces a heavy 30 dark smoke and is slow to ignite. A thick black heavy soot soon fills up the stove pipe and it is to overcome these objectionable features that this application is designed.

The primary object of the invention is to 35 produce a stove so constructed that even large quantities of slack coal may be fed into the stove without danger of exploding gases or of smothering the fire.

With the foregoing and other objects in 40 view which will appear as the description proceeds, the invention resides in the combination and arrangement of parts and in the details of construction hereinafter described and claimed, it being understood that 45 changes in the precise embodiment of the invention herein disclosed may be made within the scope of what is claimed without departing from the spirit of the invention.

In the accompanying drawings:—

50 Figure 1 represents a vertical section of a stove constructed in accordance with this invention;

Fig. 2 is a side elevation thereof with the casing in section;

Fig. 3 is a side elevation of the wind vane 55 and funnel used to supply air;

Fig. 4 is a detail plan view; and

Fig. 5 is a detail sectional view of the two way valve used.

The stove constituting this invention comprises an ash pit 1 mounted on suitable legs in the usual manner with a fire pot 2 arranged over it and having a grate 3 located between them. The upper portion of the fire box 2 is made substantially cylindrical as 60 shown at 4 and is equipped with a band 5 having openings 6 therein to permit the heat and flame from the fire box to pass out into a casing 10 which surrounds the stove proper. The casing 10 encompasses the stove from a 70 point near its top to its bottom and is closed at both ends being equipped at its lower end with a door 11 to afford access to the ash pit. A flue for the products of combustion is shown at 12 and leads from the upper end 75 of casing 10 to a chimney or other suitable point.

A magazine 13 rises from the apertured band 5 and is preferably made tapering toward its upper end to prevent packing of the 80 coal and insure its proper feeding to the fire pot. This magazine 13 is equipped at its upper end with an airtight closure 14 which closure is removable to provide for the filling of the magazine. 85

A coiled pipe 15 surrounds the magazine and fire pot of the stove within the casing 10, the upper end of said pipe extending through the top of the casing and equipped outside said casing with a two-way valve 90 16 having an opening 16^a which discharges to the atmosphere. This valve 16 shown in detail in Fig. 4 when positioned as therein shown, brings pipes 17 and 15 into communication. When the valve is turned to bring 95 opening 16^b into register with the outlet 16^a it will cut off pipe 17 and bring pipe 15 into communication with the atmosphere through openings 16^a and 16^c. The pipe 15 beyond the valve 16 connects with an air supply pipe, 100 17 which is shown broken off in the drawings but which is designed to be connected with a weather vane which when the wind blows will revolve and force air down through pipe 17 and when the valve 16 is open to bring 105 openings 16^b and 16^c into register. This air passes through the coils of pipe 15 and is heated before it leaves said coils at the bot-

tom of the stove through pipe 18 having a cut off valve 19 therein. The pipe 18 is connected with another pipe 20 which leads into a gasometer 30 for a purpose presently to be described.

The pipe 20 has a cut off valve 21 in rear of its connection with pipe 18 and a branch 20^a in front of said connection, said branch having a cut off valve 20^b. This branch 20^a 10 is designed to let the hot air out to the atmosphere. This pipe 20 which extends under the casing 10 and up to a point above the stove is also equipped with a cut off valve 20^c located between pipes 18 and 20^a. A 15 branch pipe 22 leads from the upright portion of pipe 20 and extends into the fire pot where it discharges in jets into the coal near the center of the column of coal when it is discharged from the magazine. This pipe 20^d 20 is provided outside the casing 10 with a cut off valve 22^a for controlling the air supplied through pipe 22.

The space between the casing 10 and the coils 15 is employed to carry off any smoke 25 which may be generated when the jets are partially cut off to regulate the temperature in the room.

A weather vane 25 is carried by a sleeve 26 mounted to revolve on the upper end 30 of pipe 17 and is equipped with a funnel shaped air intake 27 through which air enters and is directed through pipe 17 into the branch pipe 22 which discharges it through jets 23 into the coal in the stove.

35 It will thus be seen that when the wind blows a fire may be easily started with lignite coal as easily as with any other coal owing to the jets of air forced into the coal to promote combustion. However the wind 40 does not always blow and in order to produce the necessary draft and tide over calm days air is stored up in the gasometer 30 and then used to supply the necessary draft in time of calm when the weather vane is not 45 working.

The gasometer 30 is of usual construction being here shown mounted on a suitable stand 31 and comprising a cylindrical water container or tank 32 in which is 50 mounted to slide a gas bell 33 the inner end of which is submerged in the water tank 32. The pipe 20 extends up through the bottom of tank 32 and discharges above the water level under the bell 33. Suitable 55 weights 34 are removably mounted on the bell 33 so as to exert the desired amount of pressure on the air in bell 33, it being understood that when it is desired to use the air stored in said bell additional weights 60 are added which will force the bell downward and the air in it out through pipe 20 back up into branch pipe 22 through which it is discharged into the fire pot and commingled with the gases to promote combustion. It is of course understood that 65

before the gasometer is employed to supply draft to the furnace the valves 19 and 24 are closed.

From the above description it will be obvious that a stove constructed as herein 70 shown and described will be simple, cheap and easily installed and will be automatically controlled by the gasometer.

The gas bell 33 is preferably provided 75 with a vent valve indicated at 35 to provide for the escape of any surplus steam which may generate in the gasometer.

The apparatus here shown in connection 80 with a heating stove may obviously be used on a cook stove by very slightly changing its construction.

When desired the valves 16 and 20^c are cut off and valve 16^a opened which will cause the air entering through pipe 17 to pass down through pipe 20, up through 85 pipes 18 and 15, it being heated in its passage through pipe 15 and then out through valve 16^a to the atmosphere.

I claim:—

1. A stove of the class described including 90 a fire box having a magazine arranged thereover, a casing surrounding the stove from a point near its top to its bottom, said casing being closed at both ends, a coiled pipe within said casing surrounding the 95 magazine and fire box of the stove, the upper end of the pipe extending through the top of the casing and equipped outside said casing with a cut off valve, an air supply pipe connected with said pipe beyond 100 said valve, the lower end of said last mentioned pipe having a branch extending through the casing into the fire box and equipped with a cut off valve located outside said casing.

2. In a stove of the class described, a fire box having a magazine arranged thereover, a casing encompassing said stove and spaced therefrom terminating at its upper end near the top of the stove, a combustion flue leading from the casing, a coiled pipe arranged in said casing and surrounding the stove, said pipe extending at its upper end through the top of the casing and its lower end through the bottom of the casing, said projecting ends being provided with cut off valves, an air supply pipe connected with both of said pipe ends and having cut off valves located adjacent said pipe ends and a branch pipe leading from said air supply pipe and discharging into the fire box of the stove.

3. In a stove of the class described, a fire box having a magazine arranged thereover, a casing encompassing said stove and spaced therefrom terminating at its upper end near the top of the stove, a combustion flue leading from the casing, a coiled pipe arranged in said casing and surrounding the stove, said pipe extending at its upper end 115 120 125 130

through the top of the casing and at its lower end through the bottom of the casing, said projecting ends being provided with cut off valves, an air supply pipe connected with both of said pipe ends and having cut off valves located adjacent said pipe ends, and a branch pipe leading from said air supply pipe and discharging into the fire box of the stove, and a gasometer

connected with said lower pipe end and 10 having means whereby the air collected therein may be returned to the fire box of the stove when desired.

In testimony that I claim the foregoing as my own, I have hereto affixed my signature.

WILLIAM JOHNSTON.
